UNITED STATES PATENT OFFICE.

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE.

WELT-ATTACHING METHOD AND PRODUCT.

Application filed November 21, 1925. Serial No. 70,569.

This invention is a novel welt attaching method, and the product thereof. The invention relates especially to the manufacture of shoes by the welt system and involves an improvement in the method by which the welt strip is attached or stitched to the shoe upper and the lip of the insole. While the method of the present invention is independent of any particular mechanism, it is adapted to be carried out on shoe stitching machines of the well known type known as welt-and-turn stitching machines by a proper modification of the mode of handling and presenting the welt to the work and manipulating the cooperating instruments.

The general object of the present invention is to improve the mode of assembly and attachment of the welt, upper, and sole lip, as well as the resulting product or shoe. A particular object is to dispense with a certain factor usually employed in the manufacture of welted shoes, namely the beveling of the welt previous to its attachment, consisting in removing the diagonal corner of the welt between the attaching stitches and the edge of the welt, by which the welt is enabled to be tilted away from the shoe upper, about the bevel corner as a center, and thus satisfactorily brought into flat condition, for the attachment of the outsole. The beveling involves a loss of material, to the extent of the entire width of the beveled margin of the welt. The present invention dispenses not only with the beveling operation, itself an added expense in the manufacture of a shoe, but, by dispensing with the beveled edge, effects a material saving in leather. For example if one tenth of the width be saved this amounts to ten per cent saving in leather used, a very considerable item in the long run. A narrower width of welt strip can be used, and yet obtain the same lineal extension of welt for the purpose of subsequent attachment to the outsole. In carrying out the novel method hereof a new product is produced. Other and further objects and advantages of the present invention will appear in the hereinafter following description of an embodiment thereof, or will be apparent to those skilled in the subject. To the attainment of such objects and advantages the present invention consists in the novel welt attaching method and product, and the novel features of operation, arrangement,

combination and detail herein illustrated or described.

In the accompanying drawings Fig. 1 may be considered a right hand elevation of the parts of a welt stitching machine immediately surrounding the stitching point, with the shoe and welt indicated in fore-and-aft cross section, it being understood that the work, as usual in such machines, is fed progressively from the person viewing Fig. 1, that is in a leftward direction to a person standing at the front of the machine. This view, like the others, is diagrammatic in character.

Fig. 2 is a view similar to Fig. 1, but showing fewer of the mechanical parts, and showing them in a different stage of operation.

Fig. 3 shows a similar section of a shoe after attachment of the welt and removal from the machine, and with the elements at the left side shown trimmed and reshaped preparatory to filling the insole and applying the outsole.

Figs. 4, 5, 6 and 7 are diagrams illustrating the prevailing methods of the prior art, and the present invention compared therewith, in principle.

The shoe, during the welting operation, may be occupied by a wooden last. An outwardly projecting lip α is previously formed on the insole α' and a fabric lining α'' may be employed, covering the outer surface of the insole, and extending into the channel under the lip α , for reinforcement purposes, as already well understood. The shoe upper γ surrounds the wooden last, with its edges fastened around against the outer margins of the insole, and in face contact with the insole lip. In the welt sewing machine these assembled parts are fed progressively past the stitching point, while the welt strip w is laid in place, and held in a particular manner, according to this invention, while the attaching stitches z are applied.

Fig. 1 shows a work support or bumper A mounted on a shank a , usually intermittently locked forward, while the work or shoe bears against the bumper, as shown. The main guidance of the advancing shoe is through a channel guide B formed at the lower end of a shank b , arranged to slide in the feeding direction and to swing, so that the channel guide may partake in the intermittent feed

movements, as well understood. The needle C penetrates the welt and work between feeding movements. It is shown as a curved barbed needle carried on an oscillating needle block c, and a needle guide C' may be employed to brace the needle adjacent to the work. A looper D is put through circular movements when the needle is advanced, as seen in Fig. 1, to lay successive loops of wax thread in the barb of the needle. The shank d of the looper is suitably connected to deliver the desired loop forming movements to the looper. Another stitching instrument is the awl or feed point G, which is arranged to puncture the work adjacent to the channel guide and reciprocate with the channel guide to assist the step by step feeding motion of the work.

The various stitching instruments described may be driven from a power shaft for example in a manner as disclosed in prior patents of Zaleski et al., Numbers 1,288,366 of Dec. 17, 1918 and 1,361,952 of Dec. 14, 1920. A welt feeding guide will be understood, although omitted from Fig. 1 hereof to avoid confusing the disclosure. Such welt guide should be of such character and so located and operated as to deliver the welt to the stitching point in the proper position and posture to carry out the objects of the present invention. Such a welt guide is already shown in prior application Serial Number 21,544, filed Apr. 8, 1925, to which reference may be had for the details, and the same is indicated in dotted lines at H in Fig. 2.

The principles of the present invention may be explained in connection with the diagrams Figs. 4-7. Thus Fig. 4 indicates in principle the beveled welt w attached to the upper y by stitches z. Fig. 5 shows the same on enlarged scale. The bevel w² enables the welt when reshaped or beaten to be tilted outwardly into nearly flat condition, as seen in Fig. 6, the stitches z partaking in the tilting action. Fig. 7 shows the principles of the present invention, in which an unbeveled or plain welt strip is held in a particular posture, namely slantingly, during the formation of the stitches, so that when the stitches z are applied they will pass cornerwise from a point at the outer face of the welt through the corner at the inner side of the welt and thence through the upper. To carry this out the welt guide H must be set at the proper angle or tilt so as to present the welt to the needle to permit the stitches to pass through cornerwise, as indicated, and the welt guide must so position the welt that the inner corner thereof is substantially at the stitch line, as Fig. 7 indicates, so that when attached the welt may readily tilt about its inner corner to the desired flat angle for subsequent attachment to the outsole. The entry of the needle into

the welt at the proper point may be facilitated by preforming a gutter w' at the outer side of the welt as indicated in Figs. 1 and 2, and this gutter also accommodates the finished stitches.

Referring now to Fig. 1 it will be seen that the welt is so positioned and held during the stitching that the curved needle C enters the outer face of the welt at a point somewhat inward of its edge, but passes substantially through the inner corner of the welt, and thence through the shoe upper and the insole lip. In this way a shoe welting machine may be made to carry out the principles of the present invention.

A further preferred mode of operation is that the awl G, when swung rearwardly is caused not merely to prick the insole lip, so as to take part in the feeding, but actually to penetrate through the substance of the insole lip, and to enter the material of the upper, as shown in Fig. 2. This mode of operation of the feed point or awl serves the double advantage of giving a better grip on the work and a more positive and satisfactory feeding action, and additionally preparing a substantial aperture, entirely through the insole lip, and its lining, adapted to receive and facilitate the penetration by the needle on its next forward stroke.

When the welt has been stitched to the upper and insole lip as described, completely around the shoe, the latter is removed from the machine and prepared for the subsequent attachment of outsole. Thus as shown in Fig. 3 the welt w is reshaped or beaten into a flat condition around the shoe, and as seen at the left side of the figure the extreme edges of the upper y and the insole lip x are trimmed off substantially flush with the outer surface of the welt. Fig. 3 shows the disposition that may be taken by the described parts, and by the stitches z at this stage. Subsequently the space u between the insole and outsole may be filled with suitable filling material, and the outsole v applied and stitched to the welt, as indicated in dotted lines.

The shoe welt stitching machines of the prior patents are adaptable for this invention by dropping the welt guide so that the top or inner edge of the welt comes closer to the stitch line, and tilting it to give penetration as shown in the figures where $\frac{1}{6}$ " strip is usually necessary to afford the proper welt extension, this invention will give the same extension by using $9\frac{1}{2}$ " wide welt strip, thus saving $\frac{1}{6}$ " width or over 10%, as before stated.

It will thus be seen that there has been described a welt attaching method, and the product thereof, embodying the present invention. Since various matters of operation, arrangement, combination and detail may be modified without departing from the prin-

ciples of the invention it is not intended to limit the invention to such matters except so far as set forth in the appended claims.

What is claimed is:

- 5 1. The method of manufacturing a welt shoe comprising the step of stitching an unbeveled welt to the assembled lipped insole and lasted upper by holding the welt to the upper with its corner adjacent the work substantially in the stitching line, and applying stitches slantingly through the body of the welt and through the corner thereof into the upper and insole lip.
- 10 2. The method as in claim 1 and wherein the stitches are produced by causing the needle to enter the outer face of the unbeveled welt at a point removed from the edge and to penetrate diagonally toward the inner corner of the welt and thence through the upper and insole lip; followed by shaping the welt and attaching an outsole.
- 15 3. The method of manufacturing a welt shoe comprising preforming a gutter at the

outer face of an unbeveled welt at a point removed from the unbeveled edge, stitching 25 such unbeveled welt to the assembled insole and upper by holding the welt to the upper with its corner adjacent the work substantially in the stitching line, and applying stitches slantingly into said preformed gutter and through the body of the welt and through the corner thereof into the upper and insole lip.

4. In a manufactured shoe the assembled and attached insole, upper and unbeveled welt, said welt having a preformed gutter in its outer face at a point removed from the unbeveled edge, with a line of stitches each extending from said welt gutter diagonally through the welt and through the inner unbeveled corner thereof and through the upper and insole.

In testimony whereof, I have affixed my signature hereto.

JOHN ROGER OLIVER.
